REEL

Howard H. Talbot, Pittsburgh, Pa., assignor to
 United Engineering & Foundry Company,
 Pittsburgh, Pa., a corporation of Pennsylvania

Application December 12, 1934, Serial No. 757,154

13 Claims. (Cl. 242—78)

This invention pertains to strip winding reels and, while not necessarily so limited, relates more particularly to reels of the type used in conjunction with metal rolling mills for handling strip material, and especially to reels of the cantilever type.

Reels of this type have a single supporting bearing for their driving end while their outboard end is customarily unsupported and kept free of obstruction to permit a coil formed on the reel being readily removed. With the development of wider mills and the demand for greater tension in the strip being rolled and coiled it has become necessary in such reels to provide some means for supporting their previously unsupported outboard ends so as to prevent them from bending under the forces encountered.

With this in mind it is an object of this invention to provide a deflection-preventing brace for the outboard end of a reel of the character referred to which is comparatively simple in construction, dependable in operation, and adapted to be easily and quickly moved into and out of engagement with the reel to facilitate the removal of a coil wound upon it.

This and various other objects, as well as the various other novel features and advantages of the invention, will be apparent when the following detailed description is read in conjunction with the accompanying drawings, of which Fig. 1 is a plan view of a reel constructed in accordance with the invention; Fig. 2 a sectional view taken on the line II—II of Fig. 1; Fig. 3 a sectional view taken on the line III—III of Fig. 2; and Fig. 4 a sectional view on an enlarged scale of the outboard end of the reel.

Referring in detail to the drawings, the embodiment of the invention therein illustrated is shown as comprising a reel drum 1 which may be made in any suitable manner, many forms of which are well known in the art. For supporting this drum in the usual manner it is mounted on a drum shaft 3 which is supported at one end only in a fixed bearing stand 2 and connected to a suitable source of driving power not shown. At the outboard end of this drum shaft there is provided an anti-friction bearing assembly 4 which is adapted to receive the free end of a removable horizontally disposed deflection-preventing brace 5.

As illustrated more particularly in Fig. 4, this outboard brace-engaging bearing assembly 4 is made up of a roller bearing cage assembly 6 which is mounted on a reduced portion 3a of the drum shaft 3 with its inner end bearing against a

collar 7 that is in turn abutted against a shoulder 3b on the drum shaft 3. To securely hold this bearing cage assembly 6 in place on the drum shaft 3, an end plate 8 having a sufficient diameter to embrace the outer end of the bearing cage is fixedly secured to the end of the drum shaft by a plurality of stud bolts 9. Surrounding the bearing cage 6 there is provided a cylindrical housing cap against which the removable brace 5 is directly contacted when moved to its operative position. This housing cap consists of a slightly tapered cylindrical shell 11 and an end cover 12 which is threadedly engaged in the outer end thereof. On its inner end this shell is provided with an internal radially disposed rib 13 which is utilized to engage the inner end of the bearing cage 6 and hold the housing cap in place on the drum shaft. Opposite to such internal rib 13 an external rib, or flange, 14 is also provided on the shell 11 for limiting the inward movement of the free end of the removable brace 5. To hold the end cover 12 of the shell 11 in place a set screw 15 is threaded through the shell into contact with its threads.

From the foregoing it will be appreciated that when the bearing cage and housing cap are assembled the bearing cage 6 must be mounted in the shell 11 of the cap assembly before the two are placed on the end portion 3a of the drum shaft 3 and that the cage-engaging end plate 8 must be secured to the end of the drum shaft 3 by the bolts 9 provided therefor before the end cover 12 is screwed into the end of the shell. It will also be appreciated that once this assembly is in place the shell 11 provides a freely movable surface against which the end of the removable brace 5 may be engaged.

Referring now in detail to the removable brace 5 it comprises a main brace arm section 5a and forearm section 5b, the former being keyed for pivotal movement to a vertically disposed pivot shaft 16 which is secured in a supporting frame 18 mounted on the floor adjacent the reel or on the housing of the mill and the latter connected to the former by an elbow joint 20. This pivot shaft 16 is retained in a pair of end bearings 19 and 21 provided in its supporting frame 18 and the inner brace arm section 5a is keyed thereon adjacent the upper of these two bearings while a gear segment 23, which is utilized to swing the brace into and out of its operative position, as shown respectively in full and dotted lines in Fig. 1, is keyed to the pivot shaft 16 below the brace arm section 5a. Cooperating with such gear segment to move the brace is a gear rack 24 which

is secured to a pair of plungers 25 and 26 respectively disposed for movement in a pair of cylinders 27 and 28 suitably located in the supporting frame 18.

To permit the assembly of the plungers 25 and 26 in the cylinders 27 and 28 the latter are provided with removable heads 29 and 31, and for actuating the plungers a suitable source of fluid pressure not shown is provided and controlled in any well-known manner.

To meet the requirements demanded of the brace the brace arm sections 5a and 5b are made sufficiently strong to adequately brace the outer end of the drum shaft 3 and sufficiently long to allow the brace to be moved well out of the way of the largest contemplated coil to be wound upon the reel. The brace is also, as shown, located for operation about a vertical pivot on the mill side of the reel to thereby most effectively resist the deflection of the drum shaft due to the tensional forces in the strip being wound upon the drum.

The reason for making the brace 5 in two parts is to facilitate its movement into and out of operative position, and as will be appreciated, by breaking the brace slightly through the use of an elbow joint its length is lessened whereby allowing it to be made with considerable bearing area and at the same time permitting its being readily moved from one position to another about its supporting shaft 16.

As shown best in Fig. 2, the main brace arm section 5a of the brace which is attached to the pivot shaft 16 is made the larger of the two and is designed to receive at its outer end the adjacent end of the forearm section 5b, the two parts being held together by an elbow joint employing a hinge pin 32 and limited in their relative breaking movement by shoulders 33 and 34 and 35 and 36, respectively, formed on the abutting ends of the two parts, the shoulders 33 and 34 being disposed to prevent the parts 5a and 5b breaking at all in an outward direction and hence maintaining the brace in a straight line when it is in its operative position. The shoulders 35 and 36 on the other hand are inclined away from each other and on a sufficient angle to prevent the necessary breaking of the brace to allow the outer end thereof to freely clear the bearing shell 12 when the brace is moved into and out of operating position.

To normally maintain the brace in its broken position so that it can be readily returned from its inoperative to its operative position without manual attention, a spring 37 and plunger 38 are provided in a bore 39 in the shoulder 33 of the main brace arm 5. The inner end of this plunger is disposed to bear against the face of the shoulder 34 of the forearm section member 5b and is enlarged to engage the inner end of the spring 37 which is maintained thereon and held thereagainst under tension by a screw cap 41 which is threadably engaged in the upper end of the bore 39.

To facilitate the engagement and disengagement of the brace with the shell at the end of the reel axis, a pivoted bearing block 44 is mounted in the free end of the arm section 5b. The outer extremity of this block is cut out to engage a substantial portion of the periphery of the shell and the major part thereof disposed below the axis of the reel to best support the weight of the reel and resist bending thereof due to the tensional forces of the strip. To hold the block in the arm section 5b the latter is bifurcated and a

pin 45 is extended through the extremities thereof and a hole provided in the center of the block, the hole being larger than the pin to permit the block to freely seat itself and move with respect to the shell when the brace is moved into and out of position. To further aid in the positioning of the block the ends of its outer extremity are rounded and its inner extremity, which is also rounded, seated against a correspondingly rounded surface which in the present embodiment comprises the outer face of a sheath 46 fitted between the inner end of the block and the inner end of the opening in the arm 5b. Through the use of this sheath the construction of the brace is facilitated and a design is provided which permits shims being inserted between the sheath and the brace to take up any play which may develop as the block or sheath wears away with use.

According to the provisions of the patent statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

I claim:

1. The combination with a cantilever type reel of a removable brace for the outboard end thereof which is provided with a hinged joint intermediate its ends and operable in a direction opposing the forces developed by the pull of the material being coiled on the reel.

2. A winding reel for coiling wide material comprising a reel drum, a supporting shaft for said drum mounted at one end in a rigid bearing, a removable brace provided with a hinged joint intermediate its ends and disposed to engage the other end of said shaft and resist the bending thereof by the pull of the material being coiled, and means for moving said brace into and out of engagement with said shaft.

3. A winding reel for coiling strip material comprising a winding drum, a supporting shaft for said drum, a rigid bearing for supporting one end of said shaft, a removable brace disposed to engage the free end of said shaft and support it against bending by the pull of the stock, and a freely rotatable cap mounted on the outboard end of said shaft for the reception of said brace.

4. A winding reel for coiling strip material comprising a winding drum, a supporting shaft on which said drum is mounted, a fixed bearing for supporting one end of said shaft, a collapsible brace having a hinged joint intermediate its ends for supporting the outboard end of said shaft from bending due to the forces developed by the pull of the strip being wound on the drum, and means for moving said brace into and out of operative engagement with the shaft.

5. A strip winding reel comprising a winding drum, a supporting shaft on which said drum is mounted, a fixed bearing in which one end of said shaft is supported, a roller bearing mounted on the outboard end of said shaft, a bearing cap mounted on said bearing for free rotary movement about said shaft, and a collapsible brace disposed to be moved into and out of engagement with said bearing cap.

6. A strip winding reel comprising a winding drum, a fixed bearing support for pivotally supporting one end of said drum, a cap assembly mounted for free rotary movement on the opposite end of said drum, and a collapsible brace

arranged to be moved into and out of engagement with said cap assembly.

7. A strip winding reel comprising a winding drum, a fixed bearing member for pivotally supporting one end of said drum, a removable brace disposed to support the opposite end of the drum against deflection due to the pull of the material being wound on the reel, a bearing assembly mounted on the outboard end of said drum for receiving the end of said brace, and means for holding said bearing assembly in place.

8. A strip winding reel comprising a winding drum, a shaft on which said drum is mounted, a fixed bearing member for supporting one end of said shaft, and a pivotally mounted brace for engaging and supporting the other end of said shaft, said brace comprising a supporting section pivotally mounted on a supported pivot shaft, and a supported section pivotally connected to the free end of the supporting section and so connected thereto as to permit limited rotation of said supported section with respect to the supporting section.

9. A deflection-preventing brace for use with a cantilever type strip winding reel comprising a support, a pivot shaft mounted in said support, a brace arm keyed to said pivot shaft, a forearm section connected by an elbow joint to said brace arm for contact with the outboard end of the reel, and means for normally biasing said forearm section out of alignment with said brace arm.

10. A deflection-preventing brace for bracing the outboard end of a cantilever type strip reel, comprising a brace arm pivotally supported at one end, a forearm section connected by an elbow joint to the free end of said brace arm, a plunger mounted in said brace arm to bear against said forearm, and spring means normally urging said plunger to break said joint.

11. A deflection-preventing brace for bracing the outboard end of a cantilever type strip reel, 10 a brace arm pivotally supported at one end, a forearm section connected by an elbow joint to the free end of said brace arm, and a bearing block mounted for limited rotation in the free end of said forearm.

12. A deflection-preventing brace for bracing the outboard end of a cantilever type strip reel comprising a brace arm pivotally supported at one end, a forearm section connected by an elbow joint to the free end of said brace arm, 20 and means for rotating said brace arm assembly into and out of engagement with the outboard end of the reel.

13. A deflection-preventing brace for a shaft or the like comprising a brace arm supported at 25 one end, a forearm section connected by an elbow joint to the free end of said brace arm, and means for moving said brace arm assembly into an out of engagement with said shaft.
